UNITED STATES PATENT OFFICE.

ADOLPH J. ORTSEIFEN, OF CHICAGO, ILLINOIS.

FORM FOR CONCRETE BUILDING CONSTRUCTION.

1,325,261.

Specification of Letters Patent.

Patented Dec. 16, 1919.

Application filed October 11, 1919. Serial No. 330,026.

To all whom it may concern:

Be it known that I, ADOLPH J. ORTSEIFEN, a citizen of the United States, and resident of the city of Chicago, in the county of Cook and State of Illinois, have invented certain new and useful Improvements in Forms for Concrete Building Construction; and I do hereby declare that the following description of my invention, taken in connection with the accompanying sheets of drawings, form a full, clear, and exact specification, which will enable others skilled in the art to which the said invention appertains to make and use the same.

This invention has general reference to concrete buildings, and is especially addressed to the construction of the forms or molds for the girders, joists and floors for the production of a monolithic building structure; and it consists, essentially, in the novel and peculiar combination of parts and details of construction, as hereinafter first fully set forth and described, and then pointed out in the claims.

One of the objects of this invention is the construction of forms, made of wooden boards and timbers, which can be readily erected and knocked down for reuse in connection with sheets of suitable material for forming the side panels of the girders, and for closing the open joints at the intersection of the girder, and the joist forms.

Another object of this invention is the construction of forms which require the least number of props or supports to sustain the forms and the concrete until the latter has set and hardened sufficiently to be self-sustaining.

A further object of this invention is the construction of forms in which leakage of fluid concrete is entirely overcome.

Other objects of this invention will hereinafter fully appear.

In the erection of casting-forms for concrete buildings, considerable difficulty is experienced in preventing leaky joints, partly due to the shrinkage of the lumber employed, and particularly at those places where the forms for the joists meet the forms for the girders and for the floors. Another difficulty is met with when the forms are to be taken down to separate them from the concrete and from one another, resulting generally in the destruction of considerable lumber, which at the prevailing, almost prohibitive price of this material

makes the cost of these forms extremely high, objections which I have entirely overcome by my present invention.

In the drawings which illustrate this invention very fully, and form a part of this specification,

Figure 1 is a plan view of a portion of a complete form for casting the girders and joists of a concrete building. Fig. 2 is a 60 sectional elevation on line 2—2 of Fig. 1. Fig. 3 is a sectional elevation of a T-girder form and associated parts thereof. Fig. 4 is a sectional elevation on line 4—4 of Fig. 1, Fig. 5 is a perspective view of the box-shaped element which forms the side panels for the girders and closes the gaps between the girder and the joist forms. Fig. 6 is a 65 plan of the blank from which the box-shaped element is formed. Fig. 7 is a 70 sectional elevation on line 7—7 of Fig. 5. Fig. 8 is a sectional elevation of a girder similar to the one shown in Fig. 4, except that the element 35 of the box-shaped element is inwardly turned instead of outwardly as 75 illustrated in Figs. 5, 7 and others. Fig. 9 is a sectional elevation of a joist form slightly modified. Fig. 10 is a perspective view of the box-shaped element showing the condition illustrated in Fig. 8. Fig. 11 is 80 a plan of the blank from which the box-shaped element depicted in Fig. 10 is formed. Fig. 12 is a sectional elevation of 85 the same. Fig. 13 is a plan of the blank from which the box-shaped element shown 90 in Fig. 9 is formed.

Like parts are designated by the same characters and symbols of reference in all the various figures.

In the erection of monolithic concrete 95 buildings it is desirable that all the columns, girders, beams and connected floors are poured as fast as possible to secure integrally connected members; and for this reason the forms or molds must be as nearly 100 as possible in position for one floor. This requires a large number of boards, timbers, and planks which it is desirable to be so placed in position that they can be readily demounted and reused, especially in buildings having a multiplicity of stories the general layout of which are alike. Such a building has almost invariably one or more longitudinal girders and a considerable number of spaced apart beams or joists to 110 support the floors and the weight which the floors are calculated to carry. In Figs. 3

and 4, I show sections of a girder A, and a number of joists B, connected therewith; which members support the floor C, the whole when cast being an integrally formed 5 and homogenous structure. These elements are cast in molds consisting of many parts, as will now be described; and in this connection I may state that it is a uniform practice to make all the bays of a building as 10 near alike as possible to enable the forms being used over and over again without cutting or refitting, until they are no longer in condition for use. These forms are so constructed that those in which the joists 15 are cast are capable of being used without any intermediate supports or props, while the forms for the girders are properly supported by posts so designed as also to carry the ends of the joists adjacent the girders. 20 The forms for the joists comprise each two vertically disposed planks, designated side panels, 12, 12^a, spaced a distance apart corresponding to the width of the joists, and of proper height, and slightly less in 25 length than that of the joists when cast.

These two side panels are at their lower margins separated by spacers 13, 13^a, said spacers being timbers of approximately the same length as the side panels 12, 12^a, and, 30 preferably oblong in transverse section. They are secured to the inner sides of the side panels 12, 12^a, in any desired manner, being either nailed or screwed together, there being, however, no fastening between 35 adjacent margins of these elements 13, 13^a.

At the upper margins of the side panels there are securely attached to the outside of these panels stringers 17, 17^a, which are flush with the upper edges of the side panels 40 12, 12^a. As usual, the joists B are in spaced apart relationship; and to form the floor C, which affords the ceiling of a story, there are placed upon adjacent side panels 12, 12^a, slab panels 18, which are constructed of a 45 number of planks preferably tongued and grooved together, and secured by cleats 19, to which the planks forming the slab panel are nailed or screwed. These cleats 19 are of a length to span the space between two 50 adjacent stringers 17, 17^a, to serve as spreaders; and their ends are beveled, as at 54, Figs. 2 and 9, the object of which is to permit the side panels 12, 12^a, being spread apart for the purpose of removing 55 the joist forms, as hereinafter explained.

The form for the girder shown in vertical section in Fig. 4, consists of horizontally disposed planks 20, 20^a, of a combined width slightly in excess of the width of the girder 60 when cast. These planks 20, 20^a, are supported by props or posts 21, having across its upper end a timber 22, of sufficient length to support said bottom timbers 20, 20^a, and stringers to be hereinafter described, said 65 cross timber 22 being suitably braced by

struts 23. Medially of its length there is placed upon the timber 22, a block 24, which reaches underneath the planks 20, 20^a.

Upon the cross pieces 22, and at the sides of the girder-form there are located two 70 stringers 25, 25^a, of suitable length, which reach underneath the bottoms of the joist forms and are supported upon the cross-pieces 22 by wedges 26, 26^a, for the purpose of alining the joist forms with the girder 75 form, and also to enable the ready removal of the joist forms.

Attention is now invited to the forms for the girder A, at which the molds of the joists stop short of the sides of the girder. 80 These sides for the girder, designated by 27, 27^a, in Fig. 4, are formed, preferably, of paper board of sufficient strength to sustain the concrete between them until set; and it is, preferably, waterproofed on one 85 or both sides to prevent softening by the wet concrete. This paper board is a rectangular sheet, shown in Fig. 6 and others, which is formed into a box-like structure, as illustrated in Figs. 5, 7, 10, and 11. This 90 blank has at its transverse margins longitudinal incisions 28, 28^a, Fig. 6, and in its lower, longitudinal margin transverse incisions 29, 29^a, reaching for some distance from these margins. This blank is folded 95 at right angles longitudinally along the dotted lines 30, 30^a, parallel to the incisions 28, 28^a, and then transversely at right angles along the dotted lines 31, 31^a, the bending being in the same direction as the bending along 30. The corner portions 34, 34^a, 100 project at right angles from the end portions 33, 33^a, and the longitudinal portions 35 at right angles to the face 36, while the corner portions 32, 32^a, overlie the top portion 37, as clearly shown in Fig. 5. This paper board has the following dimensions:

The distance between the dotted lines 31, 31^a, being the length of the face portion 36, corresponds to the distance between the inner faces of the side panels 12, 12^a, of two adjacent joist-forms, the height of this face portion equals the depth of the joists; the width of the member 37 is sufficient to overlie the slab panel, and to which it is, preferably, tacked, while the members 35 are overlying the bottom timbers 20, 20^a, and are tacked thereto, and if preferred overlying each other to close the joints in these planks. The end members 33, 33^a, are tacked 110 to the inner surfaces of the side panels 12, 12^a, and the members 34, 34^a, tacked upon the spreaders 13, 13^a, and preferably overlap each other to cover the joint between the two spreader members. It will now be noted 115 that the end portions 33, 33^a, cover the gap between the ends of the joist forms and the sides of the girder when cast, and that the lower portions 34, 34^a, are over the gap 38 120 between the bottom members 20, 20^a of the 125 130

girder form and the ends of the spreaders 13, 13^a, and that the member 37 bridges the gap between the side of the girder form and the end of the slab panel, or in other words, that the portions 36 form, as a matter of fact, the sides for the girder form, and the members 33, 33^a, and 35, form continuations of the joist form and thus make tight joints between these parts and prevent leakage of the fluid matter when the concrete is being cast.

The object of leaving the gap between the girder form and the joist form is to facilitate demounting of the forms without destroying or injuring any of the wooden parts of these forms.

As illustrated in Figs. 1, 2, and 9, the side panels 12, 12^a, are tied along their lower margins by spaced apart wires 14, which wires pass underneath the spacers 13, 13^a, and are twisted together, as illustrated at 15, to draw the joint of the members 13, 13^a together and prevent leakage. In addition to serving as ties, these wires also support the reinforcing rods 15 until the concrete has been poured and set.

The demounting of the forms is accomplished in the following manner:

First remove the joist forms by knocking out the wedges 26, 26^a, and then remove the stringers 25, 25^a, the form being held in position by the tie wires 14. These wires are now cut off close to the side panels 12, 12^a, and these panels are then forced apart by driving a chisel or other suitable instrument into the joint between the spreaders 13, 13^a, which releases the side panels from the concrete and permits the joist forms to be dropped one after the other together with the slab panels and the timbers 49, the box shaped paper boards probably remaining in place, but may also come down with the side panels. The props which support the blocks 24, and the bottom boards 20, 20^a, of the girder form may remain in place for some time after the floor with its supporting girder and joists have sufficiently hardened. It will thus be noted that there can be no jamming at the intersection of the joist forms with the girder form, owing to the decided gap therebetween so that these forms will not be injured in the slightest degree when being removed, and that they will be immediately ready for reuse.

When the girder is to be of what is termed a T-girder, such as shown in section in Fig. 3, I make the form for this girder somewhat different from the form hereinbefore described, for a plain rectangular girder. In this case I provide two side panels, 39, 39^a, to form the stem D of the girder, and place spreaders 40 between these panels. I then nail to the upper edges of these side panels planks 42, 42^a, extending horizontally from the panels 39, 39^a, which

planks 42, 42^a, in conjunction with the spreaders 40, 40^a, will support the concrete after having been cast until it has hardened. This trough-shaped form comprising the members 39, 39^a, 40, 40^a, and 42, 42^a is supported upon props 43, precisely the same as the props for the rectangular girder, and by stringers 44, and wedges 45. A paper board form the same as shown in Figs. 5 and others, is tacked with its member 37 to the slab panel 18, the members 35 are tacked to the horizontal planks 42, 42^a, and the end members 33, 33^a to the inner sides of the side panels of the joist panels, thereby closing the gap 38, between the girder, and the joist forms.

In the present construction I employ no wooden side panels for the girder mold, except in the case of a T-girder, where I employ wooden side panels 39, 39^a for the lower portion or stem D of the girder A, a paper board form for the entire sides of the T-girder not being considered sufficiently rigid to form both, the stem and the head of this T-girder.

Where a plastered ceiling is required in the concrete building, I do not cut the tie-wires 14 close to the side panels of the joist form but simply untwist, and then straighten them, so that the projecting ends of the tie-wires may be used for tying the usual channel bars and metallic lathing to the concrete, in the manner heretofore employed.

In some instances it is desirable to form the joists as illustrated in Fig. 9, *i. e.* giving them the contour in cross section of a truncated cone, in view of the well-known fact that in a concrete beam the portion of the same above the neutral axis or center of gravity is in compression, while the portion of the beam below the neutral axis is in tension, and that concrete in tension has so low a factor of resistance to rupture, that in making calculations for the dimensions of a beam to carry a predetermined load, the lower portion of the concrete is not considered, the strain being taken up by the reinforcing rods. It follows that the lower portion of the beam may be considerably narrower than the upper portion above the neutral axis, thereby resulting in a reduction of the weight of the beam, and the cost of producing the same. In this case I place the side panels 12^b, 12^c, Fig. 9, at an angle to each other, and then employ a box-shaped paper-board element, the blank of which is shown in Fig. 13. It is substantially the same as the one illustrated in Fig. 6, except that the folding lines 31, 31^a, are angularly disposed to correspond to the angularity of the joist illustrated in Fig. 9, so that when folded to box-shape, the marginal portions 33, 33^a, fit the inside surfaces of the side panels 12^b, 12^c. And in this connection I may remark that instead of making the in-

cisions 28, 28^a, parallel to the longitudinal upper margin of the blank, as shown in Fig. 6, I may make them parallel to the transverse end-margins of the blank, as shown 5 in Fig. 13, so that when the blank is folded, as hereinbefore described, the corner portions 32, 32^a, overlie the marginal portion 37, as depicted in Figs. 10 and 11, a construction which has the advantage that it 10 facilitates tacking of the corner portions 32, 32^a, to the slab panel instead to the inside of the side panels, together with the portion 37.

The slab panels are narrower than the distance 15 between the side panels 12 of one of the joist molds and the side panel 12^a of the next succeeding joist mold as shown in Fig. 2, and others, thereby leaving a space 38 between the slab panel and the box-shaped 20 paper board form. These spaces are occupied by timbers 49, lying loosely upon the stringers 17, 17^a. They are preferably square at their ends where the members 33, 33^a, of the box-shaped element overlaps these 25 timbers, but they may be molded beyond these square portions, as indicated at 50, Fig. 2, which will afford fillets at the junction of the joists and the ceiling of the floor, in a manner easily comprehended.

If desired the box-shaped element hereinbefore described for forming the side panels of the girder form, and closing the gap between the girder form and the joists forms, instead of being made of paper board, which 30 I prefer owing to the fact that it is comparatively inexpensive and that it can be readily manipulated to assume the proper shape, may be made of any other suitable sheet material, including metal without de- 35 parting from the scope of my invention. In applying the paper board it is not necessary, though desirable, that it be first formed to the box-shape shown. The blank can be readily applied to the structure in the flat 40 and bent *in situ* to the form required.

Attention is now invited to the fact that in this construction no props are required to support the forms for the joists aside from the support which they receive by the 45 stringers 25, 25^a, which are carried upon the cross pieces 23 of the posts 21. This is made possible by the peculiar construction of the side panels, which, as shown in Fig. 2 and others, are formed of the stringers 17, 50 17^a, the spacers 13, 13^a, and the vertical members 12, 12^a, so that each side panel is of Z-shaped construction; and the dimensions of the members of these elements are so calculated that they will support their 55 own weight together with the predetermined load thereon plus a sufficient factor of safety to accomplish the object without any appreciable deflection of the structure.

It may also be here noted that in view 60 of the fact that in a building in course of

construction, the floors are not loaded until the building is being occupied, so that the floors for the time being need carry but their own weight. For this reason, the forms for the joists can be removed as soon 70 as the concrete is hard enough to sustain itself, and be reerected for further use, thus requiring considerably less lumber and forms when pursuing the method hereinbefore described than has heretofore been necessary to erect a concrete building. I can also erect a concrete building at less cost, with a saving of time to complete the same.

In order to readily understand why, by exercising my method of erecting a concrete 80 building, I attain these results, I believe that a brief recital of the present method now in universal vogue, will be an aid.

In a building of more than one floor, and including a basement or cellar, and frequently sub-cellars, the present practice after the foundations have been laid, is to erect the forms for the columns, the girders, and the joists for the first floor, supporting the 85 molds for the girders as well as the joists 90 upon posts, placing the slab panels, and then pouring the concrete for the columns, the girders, the joists, and the floor, and allowing the concrete to set and harden sufficiently to be self-supporting, but not necessarily hard enough to carry any additional weight. The posts, the molds for the columns, the girders, and the joists are left in place, and a second set of forms for the 95 second floor erected upon the first floor, the 100 posts for the second floor being placed over the slots on the floor below which there are the posts for the first floor, and then the second floor cast. Where time is a consideration, even a third set of molds is erected 105 upon the second floor, thereby requiring at best three sets of molds and posts for the 110 joists before the lowermost set can be removed, which removal, however, is scarcely ever attempted until all the floors of the 115 building are cast and hardened enough to permit of the removal of the forms.

It will thus be noted that the first floor has to carry the weight of all the floors above the same, because the weight of the uppermost floor is carried to the floor next below, and so forth until the first floor is reached. Now, by making the joist molds as hereinbefore described, of Z-shaped cross section and strong enough to carry the weight of the unloaded floor without supporting posts, there are no posts required for the joists of upper floors, hence no weight is carried down to the second floor. Such being the case, I can remove the joist molds 120 of the first floor as soon as the concrete has hardened enough to sustain its own weight, and immediately locate them in position for the second floor, and continue to do this 125 until all the floors are cast. Thus I require 130

but one set of joist molds, and no posts for the same, and need not wait until the first floor is hard enough to carry additional weight, but can proceed almost immediately to prepare for the casting of the second floor, etc. The saving of lumber and time for making the joist molds is considerable and results in a very material reduction in the cost of erecting a concrete building.

Of course, the molds for the girders and the posts to support them will remain in position, preferably, until all the floors have been cast.

15 And finally, it may be observed that wherever columns E, are required to support the girders, they may be constructed in any desired manner without necessitating modifications of the forms for the girders and joists hereinbefore described.

I have hereinbefore described this invention with considerable minuteness as to details of construction, but I am aware that changes therein may be made, and parts omitted without departing from the scope of this invention as defined in the appended claims.

Having thus fully described this invention, I claim as new, and desire to secure to myself by Letters Patent of the United States—

1. In the art of forming monolithic concrete structures, means for casting the girders, joists, and floors therein, which comprise in combination, a form or mold for the girders, a series of molds for the joists and floors, the ends of the molds for the joists adjacent the molds for the girders being spaced from the molds for the girders to afford a decided gap therebetween, and a 40 box-shaped element reaching from one of the joist molds to the next joist mold, said box-shaped element having members which cover the aforesaid gaps, and form a part of the girder mold.

45 2. In molds for concrete building structures to form the joists, the combination, of two, spaced apart side panels, bottom members between said side panels, said bottom members being fixed to the side panels, said 50 side panels being tied together by wires, said wires passing around the lower margins of said side panels and having their ends twisted together, and stringers at the upper margins of said side panels, said 55 stringers being secured to the outer surface of said side panels and flush with the upper edges thereof, each of said side panels being of Z-shape transversely.

3. In molds for forming the girders and 60 joists for concrete structures, the combination, with a mold for the girder of a mold for the joists, said latter molds comprising two side panels in parallel spaced relationship, bottom members or spacers at the lower 65 margins of said side panels, a series of wire-

ties passing through said side panels above said bottom spacers, said wires being passed around the lower margins and underneath said spacers, the ends of said wires being twisted together, stringers at the upper 70 margins of the side panels, said stringers being affixed to said side panels at the outer surface thereof, slab panels between adjacent side panels and supported upon said stringers, and an element reaching 75 from one side panel to the next adjacent side panel, said element having its ends turned at right angles to overlap the ends of the side panels, said element having its upper longitudinal margin overlapping the slab 80 panel and its lower longitudinal margin secured to the girder form.

4. In molds for forming the girders and joists for concrete structures, the combination, with a mold for the girder, of a mold 85 for the joists, said latter mold comprising two side panels in parallel spaced relationship, bottom members or spacers at the lower margins of said side panels, a series of wire-ties passing through said side panels 90 above said bottom spacers, said wires being passed around the lower margins and underneath said spacers, the ends of said wires being twisted together, stringers at the upper margins of the side panels, said 95 stringers being affixed to said side panels at the outer surface thereof, slab panels between adjacent side panels and supported upon said stringers, and an element reaching from one side panel to the next adjacent side panel, said element having its ends turned at right angles to overlap the ends of the side panels, said element having its upper longitudinal margin overlapping the slab 100 panel and its lower longitudinal margin secured to the girder form, the main portion of said element forming one side panel member of the girder mold. 105

5. An element for closing the gap between a girder form and a joist mold, comprising a 110 rectangular sheet of suitable material, said sheet having parallel to one of its longitudinal margins and spaced therefrom and reaching for some distance from its transverse margins, incisions, and starting from the other longitudinal margin and extending therefrom for some distance parallel to the transverse margins other incisions, said sheet being folded and refolded to afford 115 members by which said element may be secured to the molds, as described.

6. In the art of forming monolithic concrete structures, means for forming the girders, the joists, and the floors, including, in combination, a bottom board for the 120 girder form, a series of joist molds, each of said joist molds including two spaced apart Z-shaped side panels, a slab panel between each pair of joist forms, said slab panel having a series of cleats, the ends of said cleats 125 130

being beveled, said cleats reaching from one, to the next joist form and serving as a spacer for said joist form, stringers at both sides of the girder form, said stringers underlying 5 said joist form, posts, said posts having cross bars supporting the bottom of the girder form, wedges on said cross bars underneath said stringers for adjustably supporting said joist forms adjacent said girder 10 form, and an element reaching from one joist form to the next joist form, said element being of approximately box-shaped contour, the main portion of said element forming one side panel of the girder form, 15 the end portions and one lower portion of said element forming continuations of the joist form, and the upper portion covering the gap between the slab panel and the girder form, the ends of said joist forms 20 adjacent the girder form being remote from the girder form and disconnected therefrom except by the box-shaped element.

7. In the art of forming monolithic concrete structures, means for casting the girders, the joists, and the floors of the building, comprising, in combination, a girder mold, said girder mold having a bottom, stringers at the sides of the bottom board, posts under said bottom board, said posts having cross 25 bars supporting said bottom board and reaching beyond said stringers, joist molds in spaced apart relationship, said joist molds comprising each a pair of Z-shaped side 30 panels, said side panels being so arranged

as to be self-supporting and capable of sus- 35 taining the concrete for the joist and the proper portion of the floor when cast, the ends of the joist forms being remote from the sides of the girder form, said ends of the joint forms being carried upon said stringers, removable means for vertically adjusting said stringers, whereby by removing said adjusting means the joist forms may be removed as soon as the concrete has hardened 40 sufficiently to be self-supporting. 45

8. In the art of forming monolithic concrete structures, means for forming the joists, said means including, in combination, a pair of side panels in parallel spaced relationship, said side panels having each a vertically disposed member, an inwardly extending member at the lower margin of said vertically disposed member, an outwardly extending member at the upper margin of said vertical member, the inwardly extending members being disconnected from each other, the lower and upper members being rigidly secured to the vertical member, and means for tying the vertically disposed members together at their lower margins, 50 whereby said side-panels may be forced apart at the joint of the inwardly extending members by releasing said tying means to permit the removal of the joist form after the joist has been cast. 55

In testimony that I claim the foregoing as my invention I have hereunto set my hand.

ADOLPH J. ORTSEIFEN.
